PATENTED OCT. 22, 1907.

J. A. SNODDY.

PIPE.

APPLICATION FILED FEB. 21, 1907.

UNITED STATES PATENT OFFICE.

JAMES A. SNODDY, OF SEATTLE, WASHINGTON.

PIPE.

No. 868,819.

Specification of Letters Patent.

Patented Oct. 22, 1907.

Application filed February 21, 1907. Serial No. 358,577.

To all whom it may concern:

Be it known that I, JAMES A. SNODDY, a citizen of the United States, residing at Seattle, in the county of King and State of Washington, have invented certain new and useful Improvements in Pipes, of which the following is a specification, reference being had therein to the accompanying drawings.

This invention relates to conduits, more particularly to the class employed for conveying excavations of dirt 10 by means of an accompanying current of water.

The principal object of the invention is the improvement in the construction of conduits of this character whereby they are rendered more serviceable and durable.

15 A further object of the invention is to construct the conduit with a flat base so that it can be readily laid and be better adapted to withstand such strains as devices of this character are subjected to.

20 A still further object of the invention is the provision of a renewable internal liner, or false bottom, to take the wear from the conduit proper, and thus prolong its usefulness.

25 With these and other objects in view the invention consists in the novel construction and adaptation of devices as will be hereinafter described in connection with the drawings, wherein similar reference numerals designate corresponding parts in the several views.

Figure 1 is a cross sectional view of a conduit embodying my invention as employed where the pipe is 30 constructed of iron or steel; Fig. 2, a horizontal section taken through 2—2 of Fig. 1; Fig. 3, a cross sectional view of a wood stave pipe.

Referring first to Figs. 1 and 2, the conduit or "pipe" 35 as it will be hereinafter designated, is comprised of sections each of which has a flat bottom-plate 5 which is riveted to or otherwise secured so as to make watertight connections with the laterally protruding flanges 6 of an inverted U-shaped plate 7, the two parts 5 and 7 forming the pipe-easing or shell. The upper portion 40 of the plate 7 is preferably made semi-circular and from thence downwardly the side portions 7' spread outwardly, as clearly shown in Fig. 1.

The purpose of thus spreading the sides of the pipe is to increase the rigidity of the pipe and likewise furnish, with the bottom, a dove-tail-like housing for the 45 reception of the wearing bottom whereby the latter is firmly retained in operative position. The liner is comprised of an assemblage of wooden blocks which are cut from the stock so that the grain thereof will be 50 disposed as nearly as may be in a vertical direction when the blocks are positioned within the pipe. The blocks are arranged transversely of the pipe and in contact by their side-sfaces, with a plurality of blocks forming each transverse section.

In the drawings, the central longitudinal row of 55 blocks 8 are preferably formed with a slightly concave upper surface 8', a flat lower face 8", and with side faces 8''' which flare outwardly and preferably to less angles of inclination than the sides of the pipe, as before explained. The other longitudinal rows of blocks 60 9, upon each side of the central row, are individually formed of blocks having a flat bottom 9' and sides sloping to respectively correspond with the abutting surfaces 8''' and 7''' of the central blocks and the pipe walls. The upper surface 9'' of the blocks 9 are shaped to a 65 considerable angle, about 45°, and extend from the upper side edges of the blocks 8 to a height slightly below a horizontal plane projected through the axis of the circular portion of the pipe plate 7.

Referring now to the modification, illustrated in Fig. 70 3, to show an adaptation of the invention to pipe of substantially the same internal outline in cross section and composed of a plurality of wooden staves; 5'' represents the staves of the flat bottom and 7''' those of the top and sides which are preferably provided at their abutting edges with tongues and grooves, as 10, to afford interfitting joints and insure the staves being held in alignment. Bars 11 are disposed at intervals transversely of the pipe along its bottom with the ends projecting beyond the side walls of the pipe and coupled 75 to the pipe by inverted U-shaped rods, the terminals of the rods having binding nuts 13, engaging the threaded ends 12' of the rods.

The blocks employed with the form of pipe illustrated in Fig. 3 are similar in construction and arrangement to those shown in Figs. 1 and 2 excepting that in this instance the outward slope of the side-walls of the pipe is preferably confined to the lowermost staves thereof in order that the strength of the pipe structure will not be unnecessarily lessened.

Having described my invention, what I claim as new and desire to secure by Letters-Patent, is—

1. The combination with a pipe having a curved upper portion and a flat bottom and with the sides inclined outwardly and downwardly whereby the lower portion of the 95 pipe is wider than the upper portion, of a lining for the pipe composed of three rows of blocks bearing upon said flat bottom with the outer sides of the outer rows of blocks conforming to and bearing against the inclined sides of the pipe, with the central row of blocks inclined outwardly at its side edges and corresponding to and bearing against the correspondingly inclined adjacent faces of the outer rows of blocks, the upper face of the outer rows of blocks inclined upwardly and outwardly to produce a trough-like configuration to said lining.

2. The combination with a pipe having a curved top and a flat bottom and with the lower portions of the side walls inclined outwardly and downwardly, clamp bars extending transversely beneath the pipe and with their ends extending beyond the pipe, inverted U-shaped clamp rods 100 bearing over the curved side of the pipe and with their 110

ends projecting through the extended ends of the clamped bars, fastening means operating to secure said rods to said clamp bars, of a lining for the pipe composed of three rows of blocks bearing upon said flat bottom with the outer sides of the outer rows of blocks conforming to and bearing against the inclined inner faces of the pipe with the central row of blocks inclined outwardly and downwardly at its side edges and corresponding to and bearing against the correspondingly inclined adjacent faces of the outer

rows of blocks, the upper face of the outer rows of blocks **10** inclined upwardly and outwardly to produce a trough-like configuration to said lining.

In testimony whereof I affix my signature in presence of two witnesses,

JAMES A. SNODDY.

Witnesses:

PHILIP BARNES,
E. H. ALVORD.
